UNITED STATES PATENT OFFICE.

WILLIAM A. BABCOCK, OF SOUTH COVENTRY, CONNECTICUT.

AIR-COMPRESSOR.

SPECIFICATION forming part of Letters Patent No. 280,997, dated July 10, 1883.

Application filed January 28, 1882. (No model.)

To all whom it may concern:

Be it known that I, WILLIAM A. BABCOCK, of South Coventry, Connecticut, have invented certain new and useful Improvements in Air-Compressors, of which the following is a specification.

My invention relates more especially to that class of small automatic air-compressors driven by the pressure of water from the ordinary supply-pipes, and adapted to force or compress air into barrels of beer, &c., to expel the liquor therefrom to the beer-taps. Several kinds of such compressors are now made. In some kinds the pumping or air-compressing vessels, into which the water rises to compress the air, are mounted on a rocking beam, which sways up and down as the vessels alternately fill and empty, while in other cases but one large stationary vessel is used, which incloses a float which operates the water inlet and outlet valves by its rise and fall, so as to at first admit the inflow of water to compress and expel the air, and thence shift the valves to allow the outflow of the waste and the inflow of another charge of air.

My present improvement relates to the latter class of compressors; and it consists, mainly, in the combination, with the inlet and outlet valves and the rocking lever which shifts them, of a float which operates the rocking lever and a spring connected at one end with the swinging end of the rocking lever and fixed at the other end at a point beyond the pivot of the lever, whereby the lever is caused to energetically shift the valves by the action of the spring when brought past its dead-center by the action of the float.

My improvement also consists in the special construction of the water-inlet and air-inlet valves, and in details connected with the valve mechanism, and in other features, as herein-after fully set forth.

Figure 1 of the drawings annexed presents a longitudinal section of my improved air-compressor; and Fig. 2 presents a cross-section thereof on line $x-x$, looking to the left.

In the drawings, $a a'$ indicate the chamber or casing of the pump, which is adapted to form a stationary air and water tight tank or vessel, with, of course, suitable valve inlets and outlets. This vessel or chamber may be con-

structed of metal, glass, porcelain, or any other suitable material; but I prefer to make it of cast brass, in two sections, $a a'$, the lower one being in shape that of a shallow tray, with supporting-legs $b b$ and a flange, c , to meet with a similar flange, c' , on the upper section, a' , by which the two sections are firmly secured together, a packing being introduced between the flanges. The base is formed with a depression or pocket, e , at the end, in which the float moves, to allow said float to descend fully. The section a is tapering in form, as seen in Fig. 2, and is abruptly narrowed at the top, just above the water-line, for a purpose hereinafter stated. At the end in which the float moves, however, the section a' is enlarged and terminates in a dome, f , to give room for the ascent of the float, as represented in Fig. 1 and by dotted lines in Fig. 2; but these particular shapes are not essential. On the bottom of the lower section, a , is affixed an upright hollow post, g , which forms the casing of the water-inlet valve, and is perforated with a vertical bore or port, g' , which coincides with a hole through the base, with which the water-supply pipe k connects, as seen in Figs. 1 and 2. The port g' does not rise quite through the post, but is intersected near the top by a horizontal bore, g'' , which extends clear through the post, and in which is arranged a nicely-fitting cylindrical rod or sliding valve-plunger, i , which plunger, when drawn inward past the intersection of the port g' , opens the water-way, as seen in Fig. 1, and permits the water to flow into the chamber $a a'$ to expel the air therefrom, while when the plunger is slid outward past the intersection of the port g' the water-way is closed and the flow into the chamber stopped, as will be understood. It will be noted that the port g' expands into a cavity or recess around the plunger at the intersection with the bore g'' , as seen in section in Fig. 1 and dotted line in Fig. 2, thus allowing the water-pressure to bear on all sides of the plunger, and thereby rendering it always balanced in its seat, whereby its motion becomes very easy and frictionless. A slot, f' , is cut into the top of the post through the bore g'' , to reduce the amount of the bore encircling the plunger; and also permit any grain of sand or dirt which might get between the plunger

and the bore to soon find its escape at the slot by the motion of the plunger, thus enabling the valve to clean itself more readily and preventing grinding or cutting.

5 The valve-plunger *i* is connected by a link or connecting-rod, *h*, with the upright arm of an elbow-lever, *s*, pivoted near the base of the chamber, and fitted on its horizontal arm with a valve-disk, *s'*, which covers the waste or exhaust outlet *s''*, thus constituting the exhaust-valve. It will thus be seen that the water-inlet and the waste-outlet valves are directly connected together by the connecting-rod *h*, so that when the connecting-rod is moved to 10 the left the exhaust-valve is closed and the water-inlet simultaneously opened, as seen in Fig. 1, and when moved to the right the exhaust-valve will be opened and the water-valve closed, as will be understood. The valves 15 are thus operated by a rocking lever, *l*, and float *m* when actuated by the rise and fall of the water in the chamber, as will now appear. This rocking lever *l* is trunnioned between two standards, *n*, which rise from the bottom of 20 the chamber on either side of the connecting-rod *h*, as fully shown in Figs. 1 and 2. The long arm of this lever *l* projects upward, while its short arm projects downward, and is forked into two branches, *l'*, which straddle or depend 25 on either side of a lug, *h'*, projecting laterally from the connecting-rod *h*, sufficient play being allowed between the branches *l'* and the lug to allow the rocking lever to be raised to and a little beyond its dead-center before 30 either prong will closely approach the lug, as seen in Fig. 1. The lever *m'* of the ball-float *m* is trunnioned in the standards *n* just below the rocking lever *l*, as seen best in Fig. 1, and the trunnioned end is forked into two 35 branches, which project on either side of the rocking lever *l*, and are provided with set-screws *m''*, which may be adjusted to or from the lever, so as to regulate the amount of play between them, as will be understood. Now, to 40 the tip of the long arm of the rocking lever is fastened one end of a long spiral spring, *p*, the lower end of which is connected with a pin projecting from the standards *n* in position vertically under the trunnions of the rocking 45 lever and in line with the lever when on its dead-center, as seen in Fig. 1. This arrangement of spring is duplicated on the opposite side of the lever, as seen in Fig. 2, so as to 50 balance the lateral strain on the lever and 55 make the device more effective, as will be appreciated.

It will now be readily understood from the previous description, and by reference to the drawings, that the mechanism is such that if 60 the chamber be empty of water the float will be down and the rocking lever inclined to the right and the valves in the position shown in Fig. 1. The water will thus flow into the chamber, as illustrated, and gradually rise therein, 65 elevating the float with it and compressing the air before it and expelling it through the

air-outlet *r*. The air-outlet is covered by a collapsible or slit rubber valve, *r'*, which opens into the nipple *r''*, from which the compressed air is conducted by a connected tube to the 70 beer-barrels or other vessels, as will be understood, and which valve, of course, closes against the back-pressure and prevents the return of the compressed air to the pump-chamber. As the float rises with the water it also raises the 75 rocking lever *l* to its upright position, at the same time straining the springs *p p*, and the parts are so adjusted that by the time the water has arisen to its full height, as seen in Fig. 1, the float-lever will have brought the rocking 80 lever to its dead-center, or just a little beyond it, as seen in Fig. 1, and hence just as the lever passes its dead-center the spring will now react and pull it quickly and energetically to the left, causing one of the branches 85 on its forked end to strike the lug *h'* on the connecting-rod of the valves, and thus shift the valves so as to open the exhaust-outlet and close the water-inlet. Consequently the water will now run out of the chamber through 90 the outlet *s''*, and at the same time atmospheric air will enter at the top through the vent-valve *T*. As the float descends it will shift the rocking lever in the opposite position, and as the float approaches the end of its descent it will 95 bring the rocking lever past its dead-center, to the right, where the springs *p p* will now act to pull it forcibly over to the right, and thus shift the valves in the opposite direction, closing the exhaust and opening the water-inlet, when 100 the former actions will be repeated.

It will now be noted that at the point where the water has risen to its full height in the chamber and has raised the float into the position to shift the valves, as seen in Fig. 1, 105 the upper part of the chamber will still contain a small quantity of compressed air, whose pressure will bear upon the exhaust-valve and offer considerable resistance to its opening. Just at this point, however, this compressed 110 air is allowed to escape through the relief-vent *o*, which is opened by the rising of the float against the long end of the lever *n*, pivoted in the top of the chamber, and carrying a valve-disk on its short arm to control the vent *o*, as 115 shown, thereby removing the pressure from the exhaust-valve and allowing the valves to be shifted easily by the action of the rocking lever and its springs. The top of the pump-chamber, above the water-level, is hence made 120 narrow, as before described, and shown in Fig. 2, so as to reduce as much as possible the amount of compressed air which is thus allowed to escape. As soon as the float descends, 125 however, the relief-valve *o* immediately closes, as will be understood, and the air is drawn in through the vent-valve *T*, to supply the place of the outflowing water, as before described. This vent-valve has a simple and efficient construction, as may be now observed. It consists of a metal block or disk, *t'*, screwed into 130 the top of the pump-chamber and bored with

two parallel holes, v v' , the one, v' , extending clear through, and the other, v , but partly through, and intersected by a lateral bore, v'' , which opens into the air. Into this 5 hole v is dropped a small rubber puppet or check valve of the shape shown, and onto the top of the block is screwed an air-tight cap, t'' , which forms a stop to limit the rise of the valve t and a passage between the holes v and v' . It will hence be observed that when the 10 water runs out of the pump-chamber the atmospheric air will enter through the bore v'' and v , lift the puppet t , and thence flow down the bore v' into the pump-chamber.

15 The compressed-air outlet is formed through the top of an inverted cap or thimble, w , which is tightly secured on the top of the dome f of the pump-chamber, and in this thimble is enclosed a buoyant ball-valve, y . This ball normally rests on the top of the dome and leaves the air-outlet r unobstructed, the compressed air being thus free to pass from the pump-chamber through openings y' on either side of the ball, and thence out through the outlet and 20 valve $r r'$. In case, however, the water should ever rise in the pump-chamber beyond its usual height or up to the ball y , this ball will thence float up and close the air-outlet r , thus preventing the possibility of the water being 25 forced out with the compressed air into the beer-barrels or other vessels.

30 By these combined features I am enabled to form a simple, compact, and reliable air-compressor, and one in which the important part 35 of the valve mechanism is rendered peculiarly simple in construction and quick and certain in action. By the combination of the springs p p , as described, with the other parts of the valve mechanism, I am enabled to dispense 40 with considerable weight, and to render the valves much more quick and energetic in their action, and to reduce the height of the pump-chamber as well as the waste-air space in the top, which contributes greatly to economy of 45 construction and action. For example, where a weighted lever or inverted pendulum is used to shift the valves, instead of the spring-lever shown, the weighted end of the lever cannot be submerged, as the weight would then lose 50 a great portion of its effective gravity, and, furthermore, its motions would be resisted greatly by the water. The weight, to be effective, has hence to be placed at the top of the lever, above the water-level, and this in 55 turn requires that the case be made high above the water, with a special dome or chamber for the weight to swing in. This construction therefore not only requires a larger case, but also causes the waste of a large percentage of 60 air at each action of the pump, for the increased air-space at the top represents exactly a corresponding increase of loss in the compressed air, in the same way that a large clear-

ance in an engine-cylinder would represent a large loss of the motive fluid at each exhaust. 65 By the combination, however, of the spring or springs with the valve mechanism shown, this loss, together with the other objections named, is completely obviated, and a material improvement is thereby effected in pumps of 70 this class.

What I claim is—

1. In a hydraulic air-pump substantially such as described, the combination, with a pump-chamber and with a valve or valves to 75 control the flow of water into and out of the same, of the rocking lever l , float m m' , and spring p , arranged and operating substantially as and for the purpose set forth.

2. The post or casing g , formed with a bore, 80 g'' , extending through the same, and with a port, g' , connected with the water-supply, intersecting the bore g'' and extending around it, in combination with a sliding plunger, i , fitted to the bore g'' , and arranged to move to 85 and fro in the same, so as to retire within the bore and uncover the port to permit the inflow and project through the bore and cover the port to stop the inflow, substantially as and for the purpose set forth. 90

3. The combination, with the sliding plunger i , of the valve-casing g , formed with a bore in which said plunger is fitted, an induction-port, g' , intersecting said bore, and a lateral relief-slot, f , extending into said casing, across 95 the bore, and between the end of the casing, through which the plunger protrudes, and the port g' , substantially as and for the purpose set forth.

4. The air-vent valve T , consisting of the 100 block t' , formed with the ports v v' v'' , in combination with the check or puppet valve t and cap t'' , substantially as herein shown and described.

5. In a hydraulic air-pump, the elbow-lever 105 s , having one arm acting as the exhaust-valve, in combination with the connecting-rod h , connected at one end to the other arm of the elbow-lever, and with a water-inlet valve, i , connected with the opposite end of the connecting-rod, and with suitable means for operating the rod h and the valves therewith connected, substantially as herein shown and described. 110

6. In a hydraulic air-pump, the combination 115 of the connecting-rod h , having the projection h' , and arranged to operatively connect the water inlet and outlet valves, with the forked rocking lever l and mechanism for rocking the same, substantially as herein shown 120 and described.
